[57] **CLAIM**

I claim the ornamental design for the gardening applicator for delivering liquid chemicals to vegetation, as shown and described.

DESCRIPTION

FIG. 1 is a side view of a gardening applicator for delivering liquid chemicals to vegetation showing my new design, wherein the other side is a mirror image thereof; FIG. 2 is a rear view of a gardening applicator for delivering liquid chemicals to vegetation showing my new design; FIG. 3 is a front view of a gardening applicator for delivering liquid chemicals to vegetation showing my new design;

FIG. 4 is a top view of a gardening applicator for delivering liquid chemicals to vegetation showing my new design; and, FIG. 5 is a bottom end view of a gardening applicator for delivering liquid chemicals to vegetation showing my new design.
